CLAIM

The ornamental design for a combined container and shroud, as shown and described.

DESCRIPTION

FIG. 1 is a perspective view of the combined container and shroud embodying our new design;

FIG. 2 is a front view of FIG. 1;

FIG. 3 is a right side view of FIG. 1;

FIG. 4 is a rear view of FIG. 1;

FIG. 5 is a left side view of FIG. 1;

FIG. 6 is a top view of FIG. 1; and,

FIG. 7 is a bottom view of FIG. 1.

The drawings are included for the purpose of illustrating the portions of the combined container and shroud that form no part of the claimed design.

1 Claim, 3 Drawing Sheets
